DESIGN FOR A FLASHLIGHT CASING

Bernard F. Muldoon, Mountainview, N. J., assignor to Henry Hyman, Brooklyn, N. Y.

Application January 14, 1938, Serial No. 74,286

Term of patent 14 years

To all whom it may concern:

Be it known that I, Bernard F. Muldoon, residing at Mountainview, in the county of Passaic and State of New Jersey, have invented a new, original, and ornamental Design for a Flashlight Casing, of which the following is a specification, reference being had to the accompanying drawing, forming part thereof, in which the figure is a side view of the flashlight casing, showing my new design, the vertical closely spaced parallel lines near the top indicating red color.

The dominant feature of my design resides in the portions shown in solid lines.

I claim:

The ornamental design for a flashlight casing substantially as shown and described.

BERNARD F. MULDOON.
